TIMING MECHANISM

Everett M. Roeder, Merrick, N. Y., assignor to
 Remington Arms Company, Inc., a corporation
 of Delaware

Application September 22, 1938, Serial No. 231,225

5 Claims. (Cl. 175—373)

This invention relates to thermal devices for effecting the automatic and periodic closing of electric circuits.

More specifically, the invention contemplates an improved mechanism for automatically variably timing the release of one or more target throwing traps, the traps themselves being of any one of a number of types in common use such as shown in Patent No. 1,663,780. Such traps comprise a holder for a frangible target, to which is connected a throwing spring. The target holder or carrier is held in cocked position with the spring under tension and is released by suitable trigger mechanism usually operated from a distance. The connection from the trap to the operating position or "pull stand" may be either mechanical or electrical. In the game of "skeet" two separated traps are provided, both being operated from the same pull stand, the arrangement being such that either trap may be released alone or both released simultaneously. In certain matches it is necessary to provide a variable time interval between the manipulation of the release mechanism by the operator at the pull stand and the actual release of either or both of the traps to deliver a target or targets. Under the rules of the National Skeet Shooting Association this time interval varies from 0 up to 3 seconds and should be entirely out of the control of the operator. Such variable timing is introduced for the purpose of rendering the game somewhat more difficult by providing the variable and uncertain time interval after the shooter calls for a target and before the target is actually thrown. Various appliances for this purpose have been proposed hitherto and have found limited use. The present invention contemplates an improved and greatly simplified but wholly reliable electrically actuated arrangement for effecting such a delayed trap release. Means are likewise provided for disabling the timer and effecting instantaneous trap release through the same manipulative devices. For convenience, the device, which is located at the pull stand, will be referred to in its entirety as a "timer."

In the drawings:

Fig. 1 is a plan view of a timer comprising one embodiment of the present invention, the casing cover being removed.

Fig. 2 is a sectional elevation substantially on the line 2—2 of Fig. 1.

Fig. 3 is a rear elevation of the timer including the casing cover, the casing itself being omitted.

Fig. 4 is a theoretical wiring diagram.

Fig. 5 is an assembly view of the timer and control box complete, with the cord connecting these units.

Fig. 6 is a plan view of a modified form of thermally controlled timing device.

Fig. 7 is a side elevation of the device shown in Fig. 6.

Fig. 8 is a skeleton plan view of a modified form of the invention.

Fig. 9 is a vertical sectional view substantially on the line 9—9 of Fig. 8.

In the embodiment of the invention which has been selected for the purpose of illustration, the timer is enclosed in a box or casing identified generally by the numeral 10. From the lower corners of the casing supporting feet 11 project downwardly a short distance, one object of this construction being to provide clearance beneath the bottom 12 of the casing for the heads of screws by which the timer is securely held in the casing in the manner to be hereinafter described. A cover 13 is provided, the margins of said cover extending over the upper edges of the side and end walls of the casing 10 to better exclude water and foreign materials from the casing. The casing and cover are both preferably made of metal of substantial thickness; for this purpose cast aluminum is preferred.

The entire timer and switch mechanism is supported by the cover 13. From the underside of said cover depend a number of posts, shown as 14, 15, 16 and 17, these posts being so located as not to interfere with the timer and switch mechanism. To the lower ends of such supporting posts there is secured by suitable means, such as screws 18, a base plate 19 which serves as a support for various parts to be described. While the base plate may be metal, it is preferably of an insulating material, such as Bakelite, of requisite toughness and rigidity.

For the control of the external circuits, that is the circuits to the traps to be operated, three switches are provided, a preferred form of switch being shown in Fig. 3. For convenience, the two traps to be controlled will be referred to as the "high trap" and the "low trap." The switches for the two traps are similar, and means are provided for closing two circuits to release both traps simultaneously. It will be understood, however, that any desired number of traps and any desired combinations of any number of traps may be similarly controlled, each trap being provided with a suitable electric release, such for example as the release described in the aforementioned Patent No. 1,663,780. The characters "H" and

"L" will be used with reference to the "high" and "low" traps respectively. The switch for the high trap comprises two strips of spring metal 20^H and 21^H which may be provided near their free ends with contact buttons 22^H and 23^H. The spring members 20^H and 21^H are mounted upon but insulated from the underside of the base plate 19, being spaced from said plate and from each other by suitable insulating blocks identified generally by the character 24^H. Lead wires are joined to the switch members 20^H and 21^H, preferably being connected thereto by terminal pieces 25^H and 26^H extending outward from the supporting insulating blocks 24^H. The bias of the spring strips is such that the switch is normally open, that is contact buttons 22^H and 23^H are separated. To establish contact or close the switch, a suitable manipulative device is provided. This device may take the form of a plunger 27^H extending upward through the cover 13 and provided beneath said cover with a collar 28^H furnishing an abutment for a spring 29^H, the opposite end of which is received by the upper surface of the base plate 19. The lower end of the plunger 27^H projects through an aperture in the base plate above and in position to depress the switch piece 20^H and close the switch when the plunger is manually depressed.

The switch and switch operating member for the low trap are of similar construction and identified by the same reference numerals with the character "L," and need not be described. In order to close both switches simultaneously the switch members 20^H and 20^L are elongated and terminate beneath an operating plunger 30 substantially identical with the plunger 27^H and 27^L. It will be apparent that depressing the plunger 30 simultaneously closes both the high trap and the low trap switches.

The circuits for both the high trap and the low trap include an additional automatic switch, the arrangement of the circuits being such that the automatic switch, as well as one of the manual switches above described, must be closed in order to complete the circuit to either trap. The present invention comprises a novel control of the automatic switch. Means are provided for closing the automatic switch for an interval of the order of a twentieth of a second once in every three seconds, or such other interval as may be desired, and the switch mechanism is controlled in part by the thermal expansion and contraction of an electrically heated element. The heating circuit is periodically opened and closed to provide alternate heating and cooling of said element.

It is desirable that the automatic switch be one which opens and closes with a positive "snap" action, as distinguished from one in which the contacting points gradually approach and recede from each other. Switches of satisfactory characteristics are commercially available, and such a switch, known to the trade as the "Burgess-Nicro" switch, has for convenience been included in each of the two illustrative embodiments of the invention shown in the drawings. Said switch is housed in an insulating block and will be identified generally by the numeral 31. From the insulating block extend terminals or binding posts 32 and 33 and a switch controlling plunger 34. This form of switch per se is not part of the present invention, and need not be described in detail. It is sufficient to say that when the plunger 34 is in its outward position contact is made between terminals 32 and 33, and when

the plunger 34 is pressed inwardly said contact is opened and remains open until the plunger 34 is permitted to move outwardly. Both the opening and closing movement are "snap" movements, and the switch control is so biased that the plunger 34 tends to move outwardly and close the switch. Such a switch may be used in a number of ways. As shown in Figs. 1 to 4, the switch is bodily pivoted on a post 35 projecting upwardly from the plate 19. A spring 36 compressed between the side of the switch block and a suitable abutment 37 secured to base plate 19 tends to move the switch counter-clockwise (Fig. 1) about its pivot 35. The switch is held against such movement by a reach of high resistance wire 38, one end of which is secured to an anchor post 39 projecting from the plate 19, the opposite end being connected to the switch terminal 32 by suitable joining devices, such as an angle piece 40 of electrically conductive material. For convenience, wire 38 will be referred to as the "hot" wire, by reason of the fact that it is periodically heated to permit the switch 31 to move about pivot 35 under the force of spring 36.

Suitably supported opposite the switch plunger 34 is a switch operating abutment. Since it is desirable that this abutment be adjustable, it may conveniently take the form of a screw 41 provided with a manipulative or tool engaging head and threaded into the casing wall. The electric circuit in which the switch 31 and hot wire 38 are connected in series is completed by the closing of a manual "cut-out" switch 42 mounted on the timer cover plate. When the wire 38 is cold the switch 31 is closed, as heretofore described. When current is passed through the switch and the wire 38, wire 38 is heated and expands, permitting the switch to be moved about pivot 35 by spring 36. In this movement the plunger 34 engages and is depressed by abutment 41, causing the switch to open. The flow of current through wire 38 thereupon ceases, and the wire cools until it is restored to a length such that it again moves the switch clockwise against the compression of spring 36, withdrawing plunger 34 from abutment 41 and again closing switch 31; thus completing one cycle of operation.

This cycle is repeated as long as current is supplied to the circuit including switch 31 and wire 38. The frequency of the cycle is controlled by the relative positions of abutment 41 and plunger 34, and is increased by retracting the abutment 41. The reason for this is that the rate at which heat is dissipated from wire 38, and consequently the time required to cool and shorten wire 38 an amount sufficient to close switch 31, is a function of the difference between the temperature of wire 38 and the surrounding temperature. Specifically, heat is dissipated from the wire at a rate substantially proportional to the fourth power of the temperature differential. When the current is first applied to the wire it must, in order to permit the opening of the switch, be expanded by an amount equal to the distance between the end of plunger 34 and abutment 41 plus the amount of travel of plunger 34 necessary to open the switch. If this distance is substantial, the wire must be heated to a comparatively high temperature. As soon as the requisite high temperature is attained and switch 31 is opened, due to the large temperature differential heat is very rapidly dissipated and the wire quickly shortened. However, it is not restored to its length when cold, for as soon as it has shortened

by an amount equal to the travel of plunger 34, switch 31 is again closed. This occurs at a temperature far above ambient temperature, for the reason that the wire has not been shortened by the amount of the initial gap between plunger 34 and abutment 41. Thus, for a very rapid cycle the operating temperatures are relatively high.

For a slower cycle, abutment 41 is adjusted to approach or even engage and slightly depress plunger 34 when wire 38 is cold. Relatively slight expansion of the wire, effected by heating it to a comparatively low temperature, will open the switch when there is a relatively small difference between the temperature of the wire and the surrounding temperature. Under these conditions heat is radiated from the wire comparatively slowly, and a proportionately longer time must elapse before such slow radiation dissipates enough heat to enable the accompanying temperature reduction to shorten the wire by the amount necessary to again close switch 31. In either case, however, the time during which the switch is closed is short as compared with the time during which it is open. For example, in a three second cycle the switch is closed for a time of the order of one-twentieth second.

Suitable conductors are joined to the terminals of the manual and automatic switches and the hot wire 38, and extend from such terminals to terminals on a connection block 43. For greater clarity, this block has been shown in the drawings as supported by suitable means in spaced relation to base plate 19, but it will be understood that when the base plate is of insulating material the connection block may be integral therewith. The terminals on the connection block are suitably joined to conductors extending out through the timer casing in a manner to be hereinafter described. To the underside of base plate 19 are secured posts 44 of such length as to extend below the switches, connection block, etc., held on the underside of said plate. Said posts are apertured and threaded to receive screws 45 extending upwardly through apertures in the bottom 12 of the casing. It will be noted that the timer and switches are all rigidly mounted and supported from cover 13 and that the complete mechanism is held in the casing 10 by the screws 45 and can be removed therefrom by removing said screws.

A convenient and simple arrangement of the apparatus at the pull stand is illustrated in Fig. 5. A control box 65 is provided with an insulating cover plate 66 upon which are mounted three pairs of binding posts; one pair of posts B are connected to the battery or other source of current, another pair of posts H are connected to any desired form of release for the high trap, and a third pair of posts L are connected to a release for the low trap. Inside the insulating cover plate 66 appropriate connections (shown in Fig. 4) are made from the three pairs of binding posts to the four terminals of the socket part 67 of a separable plug connector, said part 67 being mounted in cover 66. The terminals of the "prong" portion 68 of said separable plug are connected to the conductors of a flexible cord 69 which passes through an aperture 70 in the casing 10 of the timer, and within the timer the four conductors are suitably joined to terminals on connection block 43, as heretofore described. This arrangement contemplates that the connection box will be permanently mounted at the pull stand; whereas the timer unit, being an instrument of some delicacy and value, can be removed

when not in use merely by disconnecting the separable plug 67-68.

The wiring for the embodiment of the invention heretofore described is illustrated in Fig. 4. 5 Current is taken from a suitable source, illustrated as a battery B. It may be remarked that it has been found in practice that an ordinary six-volt dry-cell battery of the type commonly identified as a "hot shot" will operate the timer and likewise release the magnets for two traps controlled by the timer for an almost indefinite time; one particular installation has used the same "hot shot" battery for two years on an unusually busy field. Any other source of current, 10 however, may be provided; for example, the apparatus operates equally well with current supplied by a six-volt transformer. One of the battery leads 50 is connected (in the connection box heretofore described) to the two external circuits, 15 that is the two circuits through the two traps to be operated, and is likewise connected through lead 51 to cut-out switch 42. If the switch 42 is open, depression of one of the plungers 27^H, 27^L and 30, effects instantaneous release of the trap or traps controlled by such plunger, as will presently appear. From the cut-out switch 42 current is fed by a conductor 52 to one end of the "hot" or automatic switch controlling wire 38, heretofore described. From the opposite end of the "hot" wire 38 the current passes through connecting piece 40 and terminal 32 to the automatic switch 31. The second terminal 33 of said automatic switch is connected through a conductor 54 with the second terminal of the battery. To the connecting piece 40, or the "hot" wire 38 adjacent said connecting piece, is joined a conductor 55 which feeds the terminals 21^H and 21^L of the manual switches. The terminals 20^H and 20^L of said manual switches are connected with the external circuits of the high and low traps respectively by conductors 56 and 57. The connections may be made, for example, to a release similar to that of Patent No. 1,663,780.

The operation of the device with reference to 45 the circuits indicated may be described as follows:

Consider first, instantaneous release. The cut-out switch 42 is open, so that no current passes through wire 38. Current from the battery B 50 passes by way of conductor 54 to the terminal 33 of the automatic switch 31, which in this operation remains closed. From switch terminal 32 and connecting piece 40 current passes through the conductor 55 to the manual switch blades 21^H and 21^L. Depression of one of the plungers 27^H, 27^L or 30, completes the circuit to the opposite side of the battery, through the high house trap circuit, the low house trap circuit, or both, depending upon the plunger depressed. To effect delayed timing of trap release, the cut-out switch 42 is closed. This completes a circuit from the battery through conductor 54, automatic switch 31, hot wire 38, and conductors 52, 51 and 50, back to the battery. The automatic switch now periodically opens and closes as heretofore described. Since switch 31 is a part of the circuit to either trap and is open most of the time, it is clear that to operate either or both traps one of the switch controlling plungers 27^H, 27^L and 30, must not only be depressed but held in depressed position until such time as the automatic switch 31 is closed.

It will be apparent that the structure and circuits heretofore described may be varied and modified in a variety of ways, and that various

forms of "snap" action switches may be utilized. For example, it may be considered desirable to "balance" the hot wire against a wire of similar properties which is not subjected to heat. One such arrangement is diagrammatically illustrated in Figs. 6 and 7 of the drawings. To a projection 75 upon a base plate 76 is rigidly secured a snap action switch 77, which may be of the same type as the switch heretofore described. Pivoted in trunnions 78 extending from the base plate 76 is a post 79 which is urged clockwise (Fig. 7) about its pivot 80 by suitable means such as a spring 81 tensioned between the top of post 79 and a fixed support 82. The upper end of post 79 is of reduced diameter and forms a vertical pivot for a T-bar comprising transversely extending arms 83 and 84 and a longitudinally extending arm 85. The outer portion of arm 85 is disposed opposite the switch operating plunger 86. To the arm 84 is secured one end of the "hot" or expansion wire 87, the opposite end of which is secured to a fixed support 88. To the arm 83 is secured a wire 89 identical with the expansion wire 87 and suitably attached to an adjusting screw 90 threaded into an aperture in an upturned portion 91 of the base plate 76. These parts are so adjusted that when the expansion wire 87 is cold arm 85 clears the plunger 86 by an amount sufficient to provide the desired timing, as heretofore described. When wire 87 is heated, by the passage therethrough of a current or in any other desired manner, it will be elongated and the T-bar will pivot about the point of attachment of the wire 89, being so moved by the tension of spring 81. This movement shifts the free end of arm 85 of the T-bar to the right (Fig. 6), depressing plunger 86 and opening the switch. When wire 87 is again cooled, its increased tension restores the parts to normal position, withdrawing the arm 85 from plunger 86 and closing the switch. Since wires 87 and 89 are of identical characteristics, this arrangement provides for wire variations in ambient temperature. Any change in ambient temperature merely lengthens or shortens both wires 87 and 89 by identical amounts, slightly rocking the post 79 about its pivot 80. Substantially identical tension in the wires 87 and 89 at different temperatures is maintained by spring 81. It will be understood that the circuits containing and controlled by switch 77 are similar to those illustrated in Fig. 4.

A modification of the invention, permitting of a very fine adjustment of timing, is illustrated in Figs. 8 and 9. A snap switch 100 which may be of the same type as the switch utilized in the forms of the invention heretofore described, is pivoted at 101 on a base plate 102 of insulating material. A switch operating plunger 103 is contacted by a bar 104 pivoted at 105 and joined at 106 to a spring 107 the opposite end of which is carried by a fixed support 108. An expansion wire 109 is supported between an anchor post 110 and the aforementioned bar 104. The side of the housing of switch 100 opposite the operating plunger 103 is engaged by a pin 111 extending from a lever 112 pivoted at 113. At a suitable point lever 112 is engaged by an adjustable abutment such as a screw 114 threaded into an aperture in the casing. It will be obvious that the movement of the portion of switch 100 adjacent the operating plunger 103, which is effected by change in the position of lever 112 brought about by altering the position of screw 114, is proportional to the lengths of the arms of

the various levers involved, and that any desired ratio between the movement of the control part of the switch and the advance of screw 114 may be readily secured. The leads from expansion wire 109, as well as the terminals of other electrical devices heretofore described, may be attached to connecting pieces identified generally by numeral 115 which are mounted directly upon the base plate 102, said base plate being of insulating material.

It will be obvious that the invention is susceptible to many other variations, all falling within the scope of the appended claims, which claims are to be broadly construed.

15. What is claimed is:

1. Apparatus of the character described comprising; a circuit having therein a load, a source of electric current, a manual switch biased to open position, a unitary housed snap action switch connected in series with said manual switch, said source of current and said load; and means for automatically and periodically opening and closing said snap action switch comprising a switch opening plunger projecting therefrom, an abutment adapted for engagement by said plunger whereby said switch is opened, and thermally responsive means connected to close a circuit through said source of current and said snap action switch and joined to said snap action switch housing, whereby cooling of said thermally responsive means moves said housing to withdraw said plunger from contact with said abutment.

2. Apparatus of the character described comprising; a circuit having therein a load, a source of electric current, a manual switch biased to open position, a pivotally mounted, unitary housed snap action switch connected in series with said manual switch, said source of current and said load; and means for automatically and periodically opening and closing said snap action switch comprising a switch opening plunger projecting therefrom, an abutment adapted for engagement by said plunger whereby said switch is opened, resilient means engaging said housing and urging said plunger toward said abutment, and means for controlling the movement of said housing by said resilient means comprising thermally responsive means connected to close a circuit through said source of current and snap action switch and joined to said snap action switch housing.

3. Apparatus of the character described comprising; a circuit having therein a load, a source of electric current, a manual switch biased to open position, a pivotally mounted, unitary housed snap action switch connected in series with said manual switch, said source of current and said load; and means for automatically and periodically opening and closing said snap action switch comprising a switch opening plunger projecting therefrom; adjustable means for controlling the period of such opening and closing comprising an abutment adapted for engagement by said plunger whereby said switch is opened, resilient means engaging said housing and urging said plunger toward said abutment, and means for controlling the movement of said housing by said resilient means comprising thermally responsive means connected to close a circuit through said source of current and said snap action switch and joined to said snap action switch housing.

4. Apparatus of the character described comprising; a circuit having therein a load, a source

of electric current, a manual switch biased to open position, a unitary housed snap action switch connected in series with said manual switch, said source of current and said load; and means for automatically and periodically opening and closing said snap action switch comprising a switch opening plunger projecting therefrom, an abutment adapted for engagement by said plunger whereby said switch is opened, thermally responsive means connected to close a circuit through said source of current and said snap action switch and controlling the relative positions of said abutment and said snap action switch housing, and a second thermally responsive element so associated with said thermally responsive means as to compensate for changes in ambient temperature.

5. Apparatus for the character described comprising; a circuit having therein a load, a source

of electric current, a manual switch biased to open position, a unitary housed snap action switch connected in series with said manual switch, said source of current and said load; and means for automatically and periodically opening and closing said snap action switch comprising a switch opening plunger projecting therefrom, an abutment adapted for engagement by said plunger whereby said switch is opened, thermally responsive means connected to close a circuit through said source of current and said snap action switch and controlling the relative positions of said abutment and said snap action switch housing, a support for said thermally responsive means, and a thermally responsive element adapted to shift said support to compensate for changes in ambient temperature.

EVERETT M. ROEDER.

CERTIFICATE OF CORRECTION.

Patent No. 2,263,646.

November 25, 1941.

EVERETT M. ROEDER.

It is hereby certified that error appears in the printed specification of the above numbered patent requiring correction as follows: Page 2, first column, line 36, for "plunger" read --plungers--; line 64, for "Nicro" read --Micro--; and second column, line 55, for "disspiated" read --dissipated--; page 4, first column, line 43, for "wire" read --wide--; and second column, line 51, claim 2, for "anad" read --and--; and page 5, first column, line 18, claim 5, for the word "for" read --of--; and that the said Letters Patent should be read with this correction therein that the same may conform to the record of the case in the Patent Office.

Signed and sealed this 30th day of December, A. D. 1941.
